PROCESS FOR REMOVAL OF SULPHURIC
ACID COMPOUNDS FROM HYDROCARBON
OILSWilliam Patrick Gage, Deer Park, Tex., assignor
to Shell Development Company, San Francisco,
Calif., a corporation of DelawareNo Drawing. Application August 2, 1938,
Serial No. 222,633

2 Claims. (Cl. 196—41)

This invention relates to an improvement in the treatment of hydrocarbon oils containing oil soluble substantially neutral sulphuric acid compounds such as alkyl sulphates, with aqueous solutions of alkali metal hydroxides or alkali earth metal hydroxides under hydrolyzing conditions for the purpose of removing such sulphuric acid compounds, and more particularly is concerned with the use of said alkali metal hydroxides containing small amounts of an oil soluble base to achieve said purpose.

When contacting hydrocarbon oils with sulphuric acid, as, for example, when treating cracked hydrocarbon distillates or polymerizing olefines with sulphuric acid, substantially neutral, oil soluble sulphuric acid compounds may be formed, such as sulphuric acid esters, sulphonate acid esters and possibly other compounds of unknown composition. These compounds decompose in contact with caustic alkali at elevated temperatures with formation of acids, at least a portion of which are sulphuric and sulphurous acids.

The term sulphuric acid compounds as herein used refers to oil soluble substantially neutral compounds which are formed by reaction between sulphuric acid and hydrocarbons and which are capable of liberating acids under hydrolyzing conditions. In the following disclosure, I shall repeatedly refer to hydrolysis of the sulphuric acid compounds. While it is known that at least some of the sulphuric acid compounds do undergo actual hydrolysis under the conditions which I maintain, other sulphuric acid compounds may decompose to yield acids by different mechanisms the nature of which is not definitely known. It shall however be understood that when hereinafter speaking of hydrolysis, hydrolyzing, etc., reactions other than true hydrolysis may take place in addition to true hydrolysis under the hydrolyzing conditions hereafter described.

It is known that sulphuric acid compounds such as alkyl sulphates can be hydrolyzed with water at elevated temperatures either in the absence of active chemicals, or with the aid of dilute mineral acids or alkalis. Acids in general act as catalysts for the hydrolysis, but are troublesome because they are apt to cause serious corrosion difficulties. Hydrolysis of sulphuric acid compounds contained in mineral oils with water, e. g. as the sole reagent is described in the Rettaillau Patent 2,088,216; and according to this patent temperatures above the normal boiling point of water and preferably above 250° F., and

pressures sufficient to keep water in the liquid phase at these temperatures, are required to effect such hydrolysis. This method is also subject to corrosion difficulties because of the inherent liberation of sulphuric acid. Therefore, where corrosion resistant equipment is not available, the usual practice has been to carry out the hydrolysis in the presence of a minimum amount of a strong base sufficient at least to neutralize the liberated acid. While caustic alkalis tend to prevent corrosion, they often materially reduce the rate of hydrolysis. For the last reason and also to reduce the cost of the treatment, large excesses of base over this minimum amount have in general been avoided.

Of the various bases available, sodium or calcium hydroxides are usually employed, because they are the least expensive, and strong bases are generally considered to be more effective in preventing acid corrosion than weaker bases. However, other strong bases, such as the remaining alkali metal hydroxides, ammonia, quaternary ammonium bases, etc., are operative, although their cost is very much higher than that of sodium or calcium hydroxides.

Now I have found that frequently serious corrosion results when hydrolyzing hydrocarbon oils containing sulphuric acid compounds even in the presence of an amount of caustic soda or lime substantially in excess of that required to neutralize the potentially liberated sulphuric acid. An investigation into this problem has disclosed that there appears to be a relation between the intensity of corrosion and the intensity of agitation during hydrolysis, corrosion decreasing as agitation becomes more violent. This observation has led me to believe that the corrosion which takes place in spite of an excess of caustic soda or lime is caused by liberated sulphuric or sulphonate acids which are immediately diluted but not immediately neutralized without effective agitation, or by acids which are soluble in the oil phase and which are removed therefrom only gradually by the oil insoluble aqueous caustic alkali. The more intense the mixing, the quicker are the acids absorbed by the caustic soda and the less corrosion takes place. Since the decomposition from neutral sulphuric acid compounds to free acids requires time, there will be contained in the oil during this entire period at least a small amount of unneutralized acids which are responsible for the corrosion. Therefore, as long as there is a supply of neutral sulphuric acid compounds, corrosion must be expected to pro-

ceed until all of them have been hydrolyzed and have disappeared.

In order to shorten the time lag which exists between the formation of corrosive acids and their conversion to substantially non-corrosive salts, I have added small amounts of an oil soluble base to the reaction mixture, which amounts were just sufficient to neutralize the free acids temporarily contained in the oil phase. The presence of the base in the oil has the effect of causing substantially instantaneous neutralization of the acids, whereby corrosion is effectively checked. When thereafter the salt of the oil soluble base and the monoalkyl sulphate comes in contact with the aqueous solution of caustic soda or lime, the latter displaces the oil soluble base. As a result, the oil soluble base is liberated and remains in the oil ready to neutralize further amounts of corrosive acids formed subsequently.

Time is required for the exchange of bases and transfer of the acids from the oil to the aqueous phase, and in general the rate of exchange increases with the violence of agitation. However, the influence of the intensity of agitation becomes less significant, if the salts of the oil soluble base with the acids are soluble in both the aqueous and oily phases. Under these conditions, the exchange may be quite rapid even when mildly agitating, and the amount of oil soluble base which is tied up by monoalkyl sulphates is in general smaller than if its salt were substantially insoluble in the aqueous phase.

Suitable oil soluble bases are those which are sufficiently alkaline to form with sulphuric acid substantially non-corrosive salts such as ammonia and those of the primary, secondary and tertiary amino bases, the emulsifying powers of which are insufficiently strong to produce substantially permanent emulsions of the hydrocarbons and the aqueous solution. Such emulsions, if allowed to form, are likely to cause serious difficulties. For example, the alkanolamines, such as triethanolamine, though operative, may cause difficulties because of their intense emulsification powers.

Ammonia is particularly useful because it is relatively inexpensive and its salts with many of the monoalkyl sulphates are soluble in both the oil and aqueous phases. Moreover, it is not an emulsifying agent.

The minimum amounts of oil soluble base required successfully to prevent all danger of corrosion varies with the conditions such as intensity of agitation, solubility of the base or its sulphate salts in the aqueous phase, etc., as previously pointed out, and therefore cannot be stated definitely. When using ammonia, the amounts required are in general less than about 20% and usually not more than about 10% of the total amount of base necessary to neutralize the sulphuric acid potentially liberated from the alkyl sulphates in the course of the hydrolysis. Amounts of the oil soluble base greatly in excess of the minimum required completely to prevent corrosion are of no material benefit, and on the

contrary raise the cost of the treatment and also the danger of producing harmful emulsions.

In order to accelerate the hydrolysis, I usually employ superatmospheric pressures and temperatures in excess of the normal boiling point of water.

The following example illustrates the advantages of my process:

Hydrocarbon polymers produced by polymerization of olefines by the "hot sulphuric acid" 10 polymerization process described by McAllister in A. P. I. Proceedings, volume 18, section 3, pages 78-83, November 1937, containing about .4% sulphuric acid compounds calculated as H_2SO_4 were hydrolyzed in a steel pressure tank 9' x 40' 15 equipped with open and closed steam coils. A charge of 210 to 220 bbls. of the polymers was pumped through a heater into the hydrolyzing tank, and an amount of aqueous caustic solution of 10 to 15° Bé. slightly in excess of that required 20 to neutralize all potentially liberated sulphuric acid was added thereto and passed into the tank. The contents of the tank were agitated under pressure of about 190 lbs. per sq. in. with open steam for about three hours, whereby a temperature of about 300° F. was maintained and the average concentration of the caustic soda reduced to about 1% by the condensed steam. At the end of this period, the polymers were substantially free from sulphuric acid compounds, 30 and a slight excess of free caustic soda remained. The entire charge was then withdrawn and the above procedure was repeated with a new batch of polymers.

In spite of the excess of caustic soda, serious 35 corrosion resulted within a short time. Increasing the excess of soda did not abate the corrosion. The difficulty, however, was completely overcome by adding to the mixture of polymers and caustic soda an amount of ammonia equal to about 10% of the caustic soda charged, the ammonia being introduced into the hydrolyzing tank together with the caustic soda.

I claim as my invention:

1. In the process of removing substantially 45 neutral oil-soluble sulphuric acid compounds contained in a hydrocarbon oil by treating same with an aqueous solution of a caustic alkali selected from the group consisting of alkali metal hydroxides and alkali earth metal hydroxides in 50 an amount at least equivalent to the acid potentially liberated from said sulphuric acid compounds under elevated temperature and pressure conditions to hydrolyze said compounds and to produce acids which are neutralized by the caustic alkali, the improvement comprising treating said hydrocarbon oil with said caustic alkali in the presence of an added small amount of ammonia said amount being equal to less than 20% of the equivalent of said potentially liberated acids.

2. The process of claim 1 in which the amount of ammonia equals less than 10% of the equivalent amount of potentially liberated acids.

WILLIAM PATRICK GAGE.
